Term of patent 14 years

Int. Cl. D30—02

U.S. Cl. D30—1

FIG. 1

FIG. 2

FIG. 3

FIG. 1 is a top and end perspective view of a poultry cage embodying my new design;

FIG. 2 is an end elevation of the poultry cage shown in FIG. 1; and

FIG. 3 is an end and top perspective view of the poultry cage when viewed from the end opposite from that shown in FIG. 1 and having portions broken away to show the interior.

In FIG. 1 and FIG. 3 it is to be understood that the hidden side and end in each figure correspond to the side and end shown.

I claim:

The ornamental design for poultry cage, as shown and described.
